UNITED STATES PATENT OFFICE.

SAMUEL P. SCOTT, OF HILLSBOROUGH, OHIO, ASSIGNOR TO THE STAR MANUFACTURING COMPANY, OF SAME PLACE.

CARRIAGE-CURTAIN FASTENER.

SPECIFICATION forming part of Letters Patent No. 401,720, dated April 16, 1889.

Application filed January 10, 1889. Serial No. 295,940. (No model.)

To all whom it may concern:

Be it known that I, SAMUEL P. SCOTT, of Hillsborough, in the county of Highland and State of Ohio, have invented certain new and 5 useful Improvements in Carriage-Curtain Fasteners; and I do hereby declare that the following is a full, clear, and exact description thereof, reference being had to the accompanying drawings, and to the letters of 10 reference marked thereon, which form part of this specification, in which—

Figure 1 is a side view of my improved curtain-fastener in position and a curtain buttoned thereon. Fig. 2 is a similar view showing the fastener in the position for unbuttoning the curtain. Fig. 3 is a top plan view; Fig. 4, a vertical central section of the same. Fig. 5 is a detail sectional view of the parts assembled but disunited.

20 This invention is a carriage-curtain fastener, and it is an improvement on the present state of the art, its object being to simplify and cheapen the construction of such fasteners without impairing the utility thereof.

25 Referring by letter to the drawings, A designates the fastener, which consists of four parts—a pin, B, a base-piece, D, a spring, F, and a cap-piece or head, G. Pin B is cut or stamped from wire of suitable size, or it might 30 be cast, and in making one end thereof is formed with two diametrically-opposite laterally-projecting ears, C C, the outer faces of which are flush with the end surface of the pin. The other extremity of the pin may be 35 screw-threaded or otherwise formed, so that it may be conveniently secured to the framework of a vehicle in proper position. Base D is oval-shaped in lateral section, and has a central bore, d, corresponding in diameter to 40 pin B at bottom, but enlarged at E; and e is an annular flange surrounding the outer end of bore E and projecting beyond the face of and formed with base D.

45 F is a coiled spring, which fits within enlargement E, around pin B. Head G is oval in lateral section, and has its outer face rounded off, as shown, to facilitate buttoning of the curtain thereover. g is a central bore through head G, corresponding in diameter to pin B. At the outer end of said bore, or in the rounded

55 face of head G, are diametrically-opposite pairs of notches, H H and h h, the notches H lying in line with each other and at right angles to notches h. In the under surface of head G the bore g is enlarged, as at I, the enlargement corresponding in diameter and depth to the diameter and height of flange e of the base.

55 The parts being assembled, head G is slipped on pin B until its notches H or h are engaged by the ears C C thereof. Spring F is then slipped on the pin, its end resting in enlargement I of the head. Base D is then slipped on the pin, so that the other end of spring F is received in enlargement E, and the base is 60 moved toward head G until its flange e coincides with and partly enters enlargement I of the head, which tensions spring F by compression. When thus adjusted, a blow is given by a hammer on the side of base D, thus 65 compressing the same and causing it to bind the pin securely in bore d, so that the base cannot escape therefrom, and the spring and head are thus retained on the pin between base D and ears C C. The spring forces the 70 head away from the base, so that when properly turned the head will be locked on the pin by ears C C, seating in notches h or H, and these notches are so deeply sunk in the head 75 that the ears C C and the end of the pin will 80 lie flush with the surface of the head and cannot catch or be struck by anything moving over the surface of the head, and the necessity of an arch over the head of the pin obviated. The spring F is completely hidden and 85 protected by the head and base, and the flange e directs the movement of the head to and from the base. The head can be turned on the pin by pushing it toward the base until ears C C are freed from notches H or h, and by 90 turning the head when so depressed either pair of notches may be brought into engagement with the ears and the head locked parallel with the base, which is the position it should be in when the curtain is to be buttoned or unbuttoned, or at right angles to the base, which is its position when the curtain is fastened.

95 By making the fastener of separate pieces and as described its construction is cheap- 100

ened, the parts can be more readily cast, and, again, the pin may be made of wrought metal, thus increasing its strength and durability.

In the event of breakage of one part the 5 fastener could be readily taken to pieces and the broken part replaced.

Having thus described my invention, what I claim is—

As an improved article of manufacture, the 10 herein-described four-part carriage-curtain fastening, consisting of a base-piece having a central bore enlarged at its outer end and a projecting flange around said bore, a head-piece having a central bore enlarged at its 15 inner end to receive the flange of the base-piece, and having pairs of diametrically-opposite notches in its outer face at the end of

the bore, with a coiled spring inclosed between the head and base in the enlargements of the bores thereof, and a pin passing through 20 said head, spring, and base and rigidly secured to the base only, and having a pair of diametrically-opposite ears on its outer end adapted to engage the notches of the head and lie flush with the surface thereof when locked, 25 all substantially as and for the purpose specified.

In testimony that I claim the foregoing as my own I affix my signature in presence of two witnesses.

SAMUEL P. SCOTT.
